GOLF PUTTER

Karsten Solheim, 10412 N. 37th St.,
Phoenix, Ariz. 85028

Filed Aug. 2, 1972, Ser. No. 277,334

Term of patent 14 years

Int. Cl. D21—02

U.S. Cl. D34—5 GH

FIG. 8FIG. 10FIG. 11FIG. 9

FIG. 1 is a rear view in perspective of one embodiment of my new design of a golf putter.

FIG. 2 is a rear elevation of the head of the putter shown in FIG. 1.

FIG. 3 is a front elevation of the putter head shown in FIG. 1.

FIG. 4 is a top plan view of the putter head shown in FIG. 1.

FIG. 5 is a bottom plan view of the putter head shown in FIG. 1.

FIG. 6 is an end elevation of the putter head shown in FIG. 1.

FIG. 7 is a rear view in perspective of a second embodiment of my new design of a golf putter in which a hosel is connected to the putter head proper by a straight stem having its axis in line with the shaft axis rather than an angled stem more clearly seen in FIGS. 4 and 5 for the first embodiment.

FIG. 8 is a rear view in perspective of another embodiment of my design in which a hosel is connected to the putter head proper by a stem two substantially ninety degree bends.

FIG. 9 is a rear elevation of the head of the embodiment shown in FIG. 8.

FIGS. 10 and 11 are end elevations off the heel and toe, respectively of the embodiment shown in FIG. 8.

The dominant feature of my new design of a golf putter resides in a gradual increase from heel to toe of the height and width of the club head proper in combination with the particular configuration of the undulating back portion of the club head as shown.

I claim:

The ornamental design for a golf putter, substantially as shown and described.
